UNITED STATES PATENT OFFICE.

WALLACE W. GOULD, OF BRIDGEPORT, CONNECTICUT, ASSIGNOR TO THE WARNER BROTHERS CORSET COMPANY, OF CONNECTICUT.

DESIGN FOR A CORSET.

SPECIFICATION forming part of Design No. 22,883, dated November 14, 1893.

Application filed July 6, 1893. Serial No. 479,756. Term of patent 3½ years.

To all whom it may concern:

Be it known that I, WALLACE W. GOULD, a citizen of the United States, residing at Bridgeport, in the county of Fairfield and State 5 of Connecticut, have invented and produced a new and original Design for a Corset, of which the following is a specification.

My invention relates to a design for corsets, and it consists in the ornamentation and 10 configuration as shown in the accompanying drawing, in which is shown a plan view of one section of a corset embodying my design.

The general outline of the corset is the same as those well known shapes of corsets now in 15 vogue, and it is provided with the usual stay-covering strips *a* on the outer surface of the corset body *A*, which extend from the upper to the lower edge thereof. Extending from

the top of each of the stay-covering strips nearest the front edges of each half or section 20 of the corset, are diagonal strips *b* extending downward at an inclination, to the next adjacent stay covering-strip *a*, or to the busk.

This design gives a finished and ornamental appearance to the corset. 25

What I claim is—

A design for a corset, substantially as described and shown.

In testimony whereof I have signed my name to this specification in the presence of 30 two subscribing witnesses.

WALLACE W. GOULD.
